KELLY BAR BUSHING

Charles H. Collett, Walnut Park, and Millman M. Ayres, Los Angeles, Calif.

Application April 5, 1939, Serial No. 266,126

7 Claims. (Cl. 255—23)

This invention relates to oil well tools and particularly pertains to a Kelly bar bushing for rotary well drilling equipment.

In the drilling of oil wells by the rotary method it is common practice to use a string of drill pipe at the lower end of which a drill bit is positioned, and at the upper end of which a Kelly bar is attached. The Kelly bar is usually square in section and passes through a Kelly bar bushing in the rotary table, whereby it may be free to slide vertically during drilling operation while being positively driven and rotated by the table. Under such conditions it is obvious that there is a tendency for a great amount of friction to be set up between the Kelly bar and the bushing through which it extends when driving power is applied and when the Kelly bar is moved up and down through the bushing. Various expedients have been provided for eliminating this friction. In most instances, however, the wear has been imposed at points of relatively small area which has caused the parts to be rapidly worn out and to require repair.

It is the principal object of the present invention to provide a Kelly bar bushing in which a relatively large surface area is exposed to the Kelly bar and also a relatively large surface area is provided upon the bushing, while a minimum amount of friction occurs between the various moving parts of the structure, thus insuring that the Kelly bar may move freely through the bushing without binding or excessive friction, and that at the same time the moving parts of the Kelly bar are not liable to be worn and require repair. Another object of the present invention is to provide an endless anti-friction bearing chain, particularly adapted for use in connection with the present invention but also having features rendering it of considerable advantage in various other mechanical structures.

The present invention contemplates the provision of a Kelly bar bushing having a main housing adapted to properly seat within the rotary table of a drill rig, and through which a Kelly bar may reciprocate, the bushing carrying endless anti-friction bearing elements interposed between the Kelly bar and the body of the bushing whereby free movement of the Kelly bar may be attached with a minimum amount of friction and wear.

The invention is illustrated by way of example in the accompanying drawings, in which:

Figure 1 is a view in side elevation showing the assembled Kelly bar structure as mounted within a rotary table.

Fig. 2 is an enlarged view in central vertical section through one wall of the bushing as seen on the line 2—2 of Fig. 1.

Fig. 3 is an enlarged view in vertical section through one of the endless anti-friction bearing members as seen on the line 3—3 of Fig. 2.

Fig. 4 is a view in plan showing the structure in elevation.

Fig. 5 is a view in transverse section through the side wall showing the endless bearing structure as being housed.

Fig. 6 is a perspective view of one of the roller members 28.

Fig. 7 is a perspective view of one of the disc members 29.

Referring more particularly to the drawings, 10 indicates the body of the Kelly bar bushing with which the present invention is concerned. This body is substantially square in horizontal arrangement, having vertical side walls 11, 12, 20 13 and 14. Disposed below the square portion of the body is an enlarged squared shoulder 15 below which a tapered portion 16 is formed. The tapered portion 16 fits within the usual seat 17 formed within a bushing or directly within a 25 rotary table 18. Formed through the side walls 11 to 14 and above the shoulder 15 are openings 19. These openings are substantially rectangular in shape and serve as passageways through which endless friction bearing members 20 may move. 30

Mounted upon the inner faces of each of the walls 11 to 14, inclusive, are wear plates 21. These plates, as shown in vertical section in Fig. 2 of the drawings, are indicated as having an upper overhanging flange 22 and a downward- 35 ly extending plate portion formed with a central groove 23 therein. The central groove 23 extends vertically and serves as a guide for the endless anti-friction bearing member 20. The lower end of each of the guide plates 21 has a curved surface 24 leading into the lower end of the groove while the upper end of the bearing plates have a curved surface 25, thus making it possible for the endless anti-friction bearing member to travel freely around the upper and lower edges of the plates 21 and around the outer sides of the portions of the vertical walls embraced by the anti-friction members. The plates are held in position by counter-sunk cap screws 26. These cap screws extend through slotted openings 27 in the side walls, thus making it possible to raise and lower the plates for purposes of adjustment. 40

The anti-friction bearing structures 20 are in the form of endless chains. These chains comprise roller members 28 and disc members 29 45

50

55

The roller members 28 are formed with a pair of spaced rollers 30 and 31 connected by an intermediate pin portion 32. The pin is of relatively small diameter and spaces the rollers a distance 5 apart to receive the discs 29. The roller portions 30 and 31 and the discs are of the same diameter and may be of any desired width although they are here shown as being the same width. This 10 provides an adequate transverse bearing surface 15 as well as a continuous one. The roller structures 28 are preferably made with the pins 32 and the roller elements 30 and 31 integral. However, at the end of the roller chain it is desirable 20 to provide a roller structure in which the roller portions 30 and 31 are separable. Such a structure is indicated in Fig. 3 of the drawings, where 25 it will be seen that the pin 32 has a threaded extension 33 which fits within the threaded bore of the roller 30. The roller structures and the 30 discs are not pinned together but are connected by novel anti-friction means comprising bearing balls 34 which run in complementary semi-circular ball races 35 and 36 formed in the contiguous faces of the roller sections 30 and 31 and 35 the discs 29. The bearing balls are placed within the races by the removal of a threaded plug 37 which is normally positioned within a transverse bore 38 of a diameter slightly greater than the diameter of the bearing balls. Thus, the balls 40 may be placed within this bore and then moved until they assume the interlocking positions shown in Fig. 3 of the drawings, after which the plug 37 is placed in position and will close the ball races so that the balls will stay in place and 45 will hold the roller structures 28 and the discs 29 in interlocked engagement while permitting relative rotation between the roller structures and the discs.

The length of the endless anti-friction bearing 40 structure 20 is sufficient to properly encircle the portion of the side walls between the openings 19 and the upper edge thereof and the embraced portion of the wear plates 21.

Due to some cause, the anti-friction bearing 45 structure 20 might break, in which case the parts might pass downwardly through the rotary table and into the well. This would be objectionable and in order to overcome this a ledge 39 is formed around the central opening 40 in 50 the body of the Kelly bar bushing and upon this ledge a bushing structure 41 is mounted. This structure has an overhanging lip 42 which rests upon the ledge 39 and a downwardly extending portion 43 which projects downwardly and along 55 the side faces of a Kelly bar 44. The bushing members 41 do not fit tightly against the side faces of the Kelly bar but are spaced relatively close thereto to prevent parts from passing down into the well.

60 In Fig. 2 of the drawings the endless bearing element 20 is shown as being exposed. It will be understood, however, that a construction might be used in which the bearing structure is closed, such for example as shown in Fig. 5, 65 where it will be seen that a channel 45 is formed in the back of the side wall of the bushing body, and that this is covered with a plate 46, thus concealing the length of the bearing structure which passes along the outside of the bushing.

70 In operation of the present invention the slip structure is assembled as shown in the drawings, after which the device may be mounted suitably in a rotary table. A Kelly bar is then passed through the structure. It will be understood that 75 the device has been so designed as to cause the

surfaces of the rollers 28 and the discs 29 to contact the surface of the Kelly bar while bearing against the face of the wear plate 21. As the Kelly bar moves up and down within the bushing the endless anti-friction bearing structure 20 is 5 free to adapt itself to this movement as the rollers and discs roll back and forth. It will be evident that in the event the Kelley bar moves any appreciable distance the endless bearing member 20 may pursue its path of travel one or 10 more times. It will also be evident that as the Kelley bar moves vertically the anti-friction bearing structure 20 will move, and the rollers 28 and the discs 29 will assume different positions 15 between the faces of the grooves 23 in the wear plates and the faces of the Kelly bar. This will prevent undue wear at any one point and will insure a long life to the anti-friction bearing member, while making it possible for the Kelly bar to be moved easily during driving operations 20 of the rotary table.

It will be recognized that although the endless anti-friction members have been shown as used with a Kelly bar bushing that the construction of these elements and their manner of articulate connection makes them desirable for various other uses and gives them novelty exclusive of their use in the present setting. It is to be understood also that while the Kelly bar bushing is 25 here shown as being used with a chain-like anti-friction structure that the invention is not limited to this construction but includes any type of 30 moving bearing element which has relative bodily movement with relation to the bushing as well 35 as the Kelly bar.

It will thus be seen that the structure here disclosed, while simple in operation and arrangement, provides an effective bearing structure for reciprocating members such as the Kelly bar of 40 a drill rig whereby rotation may be imparted 45 readily to the Kelly bar while permitting it to have free longitudinal movement.

While we have shown the preferred form of 50 our invention as now known to us, it will be understood that various changes may be made 45 in combination, construction and arrangement of parts by those skilled in the art, without departing from the spirit of our invention as claimed.

Having thus described our invention, what we 55 claim and desire to secure by Letters Patent is: 1. In combination with a rotary table and a Kelly bar adapted to be driven thereby, a Kelly bar bushing mounted on the rotary table and through which the Kelly bar extends, guide means on the Kelly bar bushing and extending longitudinally thereof, and endless anti-friction members carried by the Kelly bar bushing and interposed between said bushing and the Kelly bar, comprising a plurality of rollers having 60 annular grooves in their opposite faces, intermediate rollers of the same diameter having annular grooves in their opposite faces and being disposed in overlapping relation with the grooves 65 of the contiguous faces of the first mentioned rollers, and ball members positioned within the overlapping grooves of the pairs of rollers for articulately interlocking the rollers together.

2. An endless anti-friction member comprising 70 pairs of rollers, other rollers intermediate said pairs of rollers, and means articulately connecting the pairs of rollers and the other rollers, said articulate means comprising ball members positioned within overlapping grooves formed on 75

the contiguous faces of the first and second mentioned rollers.

3. An endless anti-friction structure comprising pairs of rollers laterally spaced from each other, intermediate rollers disposed with their edges between the edges of said pairs of laterally spaced rollers, and articulate means between the overlapping edges of said pairs of rollers and intermediate rollers whereby all of said rollers 10 are free to rotate on their independent axes.

4. An endless anti-friction bearing structure comprising pairs of rollers rigidly spaced from each other, said rollers having an annular groove in their opposing faces, intermediate rollers of 15 the same diameter as the first mentioned rollers and having annular grooves in their opposite faces and being disposed in overlapping relation with the grooves of the contiguous faces of the pair of rollers, and ball members positioned with- 20 in the overlapping grooves of the pairs of rollers and the intermediate rollers for articulately interlocking the rollers together.

5. In combination with a rotary table and a Kelly bar adapted to be driven thereby, a Kelly 25 bar bushing mounted on the rotary table and through which the Kelly bar extends, guide means on the Kelly bar bushing and extending longitudinally thereof, an endless anti-friction structure carried by the Kelly bar bushing and 30 interposed between said bushing and the Kelly bar, said anti-friction structure comprising a pair of rollers laterally spaced from each other, intermediate rollers disposed with their edges be- 35 tween the edges of said laterally spaced rollers, and articulate means between the overlapping edges of said pair of rollers and intermediate rollers whereby all of said rollers are free to rotate on their independent axes.

6. In combination with a rotary table and a Kelly bar extending therethrough to be rotated thereby, a Kelly bar bushing carried by the rotary table and through which the Kelly bar extends, an anti-friction means disposed between the Kelly bar bushing and the rotary table comprising a pair of rollers laterally spaced from each other, other rollers intermediate said pairs of rollers, annular grooves formed in the contiguous faces of both mentioned rollers, and ball members positioned within the overlapping grooves of both mentioned rollers for articulately interlocking the rollers together. 5

7. In combination with a rotary table and a Kelly bar adapted to be driven thereby, a Kelly 15 bar bushing mounted on the rotary table and through which the Kelly bar extends, guide means on the Kelly bar bushing extending longitudinally thereof, and an anti-friction means carried by the Kelly bar bushing and interposed 20 between said bushing and the Kelly bar, said anti-friction means being free to move longitudinally of the Kelly bar while providing a bearing support between the Kelly bar bushing and the Kelly bar, said anti-friction means comprising 25 pairs of rollers rigidly spaced from each other, said rollers having an annular groove in their opposing faces, intermediate rollers of the same diameter as the first mentioned rollers and having annular grooves in their opposite faces 30 and disposed in overlapping relation with the grooves of the contiguous faces of the pair of rollers, and ball members positioned within the overlapping grooves of the pairs of rollers and the intermediate rollers for articulately inter- 35 locking the rollers together.
